UNITED STATES PATENT OFFICE.

CLARENCE E. McCORMICK, OF YOUNGSTOWN, OHIO.

DESIGN FOR A TREAD FOR AUTOMOBILE-CASINGS.

59,245.

Specification for Design.

Patented Oct. 4, 1921.

Application filed February 21, 1921. Serial No. 446,965. Term of patent 7 years.

To all whom it may concern:

Be it known that I, CLARENCE E. McCORMICK, a citizen of the United States, residing at Youngstown, in the county of Mahoning and State of Ohio, have invented a new, original, and ornamental Design for Tread for Automobile-Casings, of which the following is a specification, reference being had to the accompanying drawing, forming part thereof.

The figure is a plan view of a tread for automobile casings, showing my new design.

I claim:

The ornamental design for a tread for automobile casings, as shown.

CLARENCE E. McCORMICK.

Witnesses:

H. W. LEFFINGWELL,
IRVING WOOLFORD.
